UNITED STATES PATENT OFFICE.

CHARLES L. HOPKINS, OF CHICAGO, ILLINOIS, ASSIGNOR TO THE CUR-
TAIN SUPPLY COMPANY, OF NEWARK, NEW JERSEY, A CORPORATION
OF NEW JERSEY.

CURTAIN-FIXTURE.

No. 804,317.

Specification of Letters Patent.

Patented Nov. 14, 1905.

Application filed June 13, 1904. Serial No. 212,364.

To all whom it may concern:

Be it known that I, CHARLES L. HOPKINS, a citizen of the United States, residing at Chicago, in the county of Cook and State of Illinois, have invented certain new and useful Improvements in Curtain-Fixtures, of which the following is a specification.

My invention relates to improvements in curtain-fixtures of that general type wherein a spring-actuated curtain or shade is provided at its lower end with a curtain-stick carrying spring-pressed heads or shoes adapted to frictionally engage the sides of the casing or grooves therein to hold the curtain at any adjusted position against the pull of the curtain-roller.

My invention has for its principal object the production of an improved and simplified fixture wherein the roller or rollers carried by the heads may be made to perform the double function of friction devices to hold the curtain when the curtain-stick is in normal or horizontal position and of antifriction devices to permit the automatic self-righting of the curtain when the curtain-stick is canted. With this object in view the invention employs as its chief distinguishing characteristic and in association with the head and one or more rollers carried thereby a brake member which is pivoted between its ends in or on the head and on one side of the pivot and is adapted to frictionally engage a roller and on the other side of its pivot projects into contact with the surface of the casing engaged by the head and under the resistance of the casing opposed to the thrust of the curtain-stick spring applies the brake to the roller when the fixture is normal or horizontal, while releasing the roller and permitting it to act as an antifriction device for self-righting purposes when the fixture is canted.

My invention in its preferred form is illustrated in the accompanying drawings, wherein—

Figure 1 is an elevational view of a portion of a curtain carrying one end of the fixture, the latter being shown partly in vertical section and in the normal or horizontal position. Fig. 2 is a similar view of the same parts, but showing the fixture in an inclined or canted position; and Fig. 3 is a face view of the head or shoe of the fixture.

Referring to the drawings, 5 indicates a

fragment of the lower portion of a window or other curtain in and transversely of which is mounted the usual hollow curtain-stick 6, the latter carrying in each end the shank 7 of a hollow head 8, normally pressed outwardly by the curtain-stick spring 9. In the opposite ends of the head are rotatably mounted 60 rollers 10, between which are mounted on pivot-pins 11 a pair of duplicate inversely-disposed brake members 12. These brake members may take a variety of forms within the purview of the invention; but they are 65 herein shown as levers consisting each of a reversely-curved bar pivotally mounted at a point somewhat outwardly of its longitudinal center and having on its outer end a brake-surface 11^a, located adjacent to and in rear of 70 the roller 10, while its forward or front face inwardly of the pivot 11 is rounded or convexed to have a bearing, as at 11^b, against the surface of the casing on the bottom wall of a groove therein, (conventionally indicated by 75 the line 13.)

In operation when the fixture is in its horizontal or normal position the outward thrust of the curtain-stick spring, acting through the head, forces the convex faces 11^b of the 80 brake members into contact with the casing, and the resistance of the latter thus acting upon the longer arms of the levers in the opposite direction throws the short outer arms of the levers into braking or retarding engagement with the wheels 10, which latter are thus made to frictionally engage by their peripheries the wall or surface 12 of the casing, thus holding the fixture against upward movement in opposition to the pull of the curtain-roller spring. This frictional engagement of the braked rollers with the wall of the casing may be augmented by the friction effect produced by the engagement of the levers with 85 said wall, or where the frictional holding 90 effect of the braked rollers is ample the wall-engaging surfaces of the levers may be made hard and smooth, so as to have little or no frictional holding effect upon the wall, it being understood that the chief function of the 100 brake-levers is to brake or retard the rollers when the fixture is horizontal in the manner already described, although their wall-contacting surfaces may be roughened or otherwise frictionized to create an auxiliary holding effect when necessary or desirable. When 105

now the curtain-stick becomes inclined or canted, as shown in Fig. 2, the resistance effect offered by the casing to the curtain-stick spring through the brake-levers 12 is intermitted or relieved, whereupon the brake-levers may swing by gravity into positions such as to retract their braking surfaces from the rollers, or at least relieve the pressure upon the latter, thus permitting said rollers to rotate freely and converting them from friction devices into antifriction devices instantly responsive to the pull of the curtain-roller spring to effect the self-righting of the fixture, whereupon they are instantly reconverted into friction devices to hold the fixture in the position assumed by it at the end of the self-righting operation.

It is evident that numerous changes and modifications of the particular structure herein shown and described might be made by those skilled in the art without departing from the spirit or principle of the invention, and hence I do not limit the latter to the construction and arrangement shown and described except to the extent indicated in specific claims.

I claim—

1. In a curtain-fixture, the combination with a curtain-stick, of a spring-pressed head movably mounted in said stick, a roller in said head adapted to act as an antifriction member when the stick is canted, and a brake member pivoted between its ends in said head and rendered operative to engage the roller by contact with the casing when the fixture is in a normal or horizontal position.

2. In a curtain-fixture, the combination with a curtain-stick and a head mounted on the end thereof, of a roller mounted in said head, and a pivoted brake member also carried by said head, said brake member having one end normally projecting into contact with the surface of the casing and on its other end carrying a brake-surface adapted to engage said roller under the resistance of the casing opposed to the thrust of the curtain-stick spring when the fixture is in normal or horizontal position.

3. In a curtain-fixture, the combination with a curtain-stick and a head mounted on the end thereof, of a roller mounted in said head, and a brake-lever also pivoted between its ends in said head, said brake-lever having one end normally projecting into contact with the surface of the casing and its other end adapted

to engage said roller when the fixture is in normal or horizontal position.

4. In a curtain-fixture, the combination with a curtain-stick and a head mounted on the end thereof, of a roller mounted in said head, and a brake-lever also pivoted in said head, said brake-lever having one end projecting into contact with the surface of the casing and its other end operatively engaging said roller under the thrust of the curtain-stick spring acting to press the opposite end of the brake-lever against the casing when the fixture is horizontal, and having its braking effect wholly or partially relieved when the fixture is canted.

5. In a curtain-fixture, the combination with a curtain-stick and a head mounted on the end thereof, of a pair of rollers mounted in the head on opposite sides of the longitudinal center of the latter, respectively, and a pair of inversely-disposed pivoted brake-levers carried by said head between said rollers, the adjacent inner ends of said brake-levers projecting into contact with the casing and their opposite ends carrying brake-shoes adapted to be forced into engagement with their respective rollers under the thrust of the curtain-stick spring acting to press the inner ends of said levers against the casing.

6. In a curtain-fixture, the combination with a curtain-stick and a head mounted on the end thereof, of a pair of rollers mounted in the opposite ends of the head, respectively, and a pair of inversely-disposed brake-levers pivoted in said head between said rollers, the adjacent inner ends of said brake-levers projecting into contact with the casing and their opposite ends carrying brake-shoes adapted to be forced into engagement with their respective rollers under the thrust of the curtain-stick spring acting to press the inner ends of said levers against the casing.

7. In a curtain-fixture, the combination with a curtain-stick, of spring-actuated heads mounted therein, said heads each having a roller and a non-rotatable independent pivoted brake member adapted to be thrown into engagement with the casing and the roller through the outward pressure of the curtain-stick spring.

CHARLES L. HOPKINS.
